UNITED STATES PATENT OFFICE.

CARLOS F. DÁRDANO, OF SAN SALVADOR, SAN SALVADOR.

SHOWER-BATH APPARATUS.

1,145,568.

Specification of Letters Patent. Patented July 6, 1915.

Application filed December 10, 1914. Serial No. 876,577.

To all whom it may concern:

Be it known that I, CARLOS F. DÁRDANO, a citizen of the Republic of San Salvador, Central America, residing at San Salvador 5 city, San Salvador, Central America, have invented certain new and useful Improvements in Shower-Bath Apparatus; and I do hereby declare the following to be a full, clear, and exact description of the invention, 10 such as will enable others skilled in the art to which it appertains to make and use the same.

The present invention relates to shower bath apparatus, and has for an object to 15 provide an apparatus of this character which will be embodied in an article of furniture, capable of transportation, and constructed in imitation of a wardrobe; and the same may be located in a sleeping or 20 other apartment where the apparatus will occupy a minimum of space.

It is another object of the present invention to provide an improved shower bath apparatus which, when in closed position, will 25 present a decorative appearance, concealing the construction of the apparatus so that the nature thereof is not disclosed.

A further object of the present invention resides in providing a shower bath apparatus which will be durable in construction 30 and easily operated in moving the same into open and closed positions; and the same will moreover be arranged to be liquid-tight so as to prevent the accidental spraying or 35 spilling of water upon the floor of the apartment.

With these and other objects in view the invention consists in the novel details of construction and combinations of parts 40 more fully hereinafter disclosed and particularly pointed out in the claims.

In the accompanying drawings forming a part of this application, and in which similar reference symbols indicate corresponding parts in the several views: Figure 45 1 is a perspective view of a shower bath apparatus constructed in accordance with the present invention, and illustrated in open position ready for use. Fig. 2 is a similar 50 view disclosing the apparatus in partly folded position. Fig. 3 is a longitudinal vertical sectional view of the apparatus in open position. Fig. 4 is a transverse sectional view of the same. Fig. 5 is a view 55 similar to Fig. 3, and illustrating the apparatus in closed position; Fig. 6 is a longi-

tudinal vertical sectional view of the apparatus disclosing a modified form of counterbalance. Fig. 7 is a cross sectional view taken on the line 7—7 of Fig. 5.

Referring more particularly to the drawings, wherein one embodiment of the present invention is illustrated, 1 designates a frame or cabinet constructed in imitation of a wardrobe or other article of furniture; the 60 same being further constructed with a head-piece 2, providing a reservoir, and a base 3 constituting a waste tank. The reservoir 2 is arranged to be supplied with water from any suitable source through a pipe 4 under 65 the control of a valve 5; or the same may be provided with mechanism for maintaining a constant level of water. From the waste tank 3 leads a pipe 6, under the control of a valve 7, for conveying away the waste 70 water, as will be understood.

The front wall 8 of the cabinet 1 is hinged, as indicated at 9, and provided with flanges 10 for converting the same into a floor or trough for the apparatus, upon 75 which the bather may stand, or upon which a bath tub may be placed. The wall 8 is provided with hinged feet 11, which may be folded down when the apparatus is closed, as indicated in Fig. 5, and the same are 80 preferably of a length to support the trough inclined, so that the waste water will drain off into the tank 3. At either side of the furniture the trough 8 is arranged to be connected at its outer end to the cabinet 1 by a 85 pair of braces 12 and 13, pivoted together, as indicated at 14, and pivotally connected at their outer ends, respectively, to the cabinet and trough. To the central connections 14 are also pivoted braces 15, connected with 90 the upper end of a frame 16, in which are mounted the doors 17, through which access may be had to the bath. The door frame 16 is further connected by means of braces 18 to the trough 8, and as advantageously disclosed in Figs. 1 and 3, the braces 18 are 95 hinged to the door frame 16 substantially midway the height thereof, and are pivoted at their lower ends to the outer end of the trough 8.

To assist in moving the trough 8 about its pivotal connection 9 in opening and closing the apparatus, it is desirable to provide a counterbalance mechanism; and for this purpose it is to be understood that any suitable counterbalance may be employed. 100 However, the counterbalance arrangement

here illustrated is the one preferably employed in the practical embodiment of the invention, and the same consists in a pair of cords 19 and 20, at each side of the apparatus, and connected at one end, respectively, to the trough 8, as indicated at 21, and to the door frame 16, as indicated at 22; and at the opposite ends of the cords 19 the same are connected to the cords 20, as indicated at 23, and the ends of the cords 20 support counterbalance weights 24. Each cord 19 runs over a pair of pulleys 25 and 26, journaled on the side walls of the cabinet 1; and the cord 20 is arranged to operate upon similar pulleys 28, likewise supported in the cabinet 1.

To the reservoir 2 is pivotally connected, by means of a ball and socket or other suitable joint, a gooseneck 29, to which is connected a spray head 30. As indicated in Figs. 1 and 3, when in open position, the spray head 30 is arranged to be suspended substantially centrally over the apparatus and when in closed position the gooseneck 29 will fold down within the cabinet 1, as illustrated in Fig. 5. In order to render this action automatic, the gooseneck 29 is connected to a pair of cords 31, or other flexible connections, the same running over pairs of pulleys 32 and 33 and having their lower ends secured to the trough 8, as indicated at 34. It will be understood that, by this construction, the trough 8, when folded down to the open position, will draw upon the connections 31 and thereby move the gooseneck 29 about its pivotal connection into a position to bring the spray head 30 substantially centrally above the apparatus.

As shown in Figs. 1 and 2, rubber or other curtains 34' and 35 are suspended at each side of the apparatus from the cords 20, secured at their opposite ends to the cabinet 1 and door frame 16, respectively. The curtain rings shown, or other suitable devices, may be employed for suspending the curtains, and the same have their lower edges disposed within the longitudinal flanges 10 of the trough 8, so as to direct the water from the spray head 30 into the trough, and prevent the water from accidental spraying or spilling over the sides of the apparatus.

Referring more particularly to Fig. 6, I have disclosed a modified form of counterbalance, the same consisting of stepped supports 36 mounted within the cabinet 1, and in vertical alinement with the counterbalance weights, which, in this instance, are suspended from the inner ends of the cords 20, as heretofore described. Each counterbalance consists of a plurality of weights 37, 38 and 39 of progressively decreasing diameters, independently slideable on the cord 20 and flanged, as shown, to engage the respective steps of the supports 36. It will be understood that in folding the apparatus,

the counterbalances will descend into the supports 36, and the weight 37 will first encounter the uppermost supporting surface, so that its effect will be withdrawn from the counterbalance after the trough 8 has been lifted through a certain predetermined distance. Upon the further upward movement of the trough 8 the weights 38 and 39 will successively engage their respective supporting surfaces and withdraw their effects to 75 counterbalance said trough. It will be understood that with this modified form of counterbalance the initial movement of the trough 8 is assisted and its inertia overcome by a combination of each of the weights of 80 the counterbalance; while, after the trough 8 has been raised, and the use of a heavy counterbalance is no longer necessary, the weights are successively withdrawn in order to prevent the apparatus too quickly and 85 violently closing. In releasing and lowering the trough 8 it will be appreciated that upon the initial movement of the same the weights of the counterbalance will not be brought into play, thereby facilitating this 90 movement, but the same will be successively brought into action as the trough descends and its weight is removed from the pivot point 9.

In operation, it will be understood that 95 from the folded position of the apparatus, shown in Fig. 5, the same may be opened for use by disengaging the front wall 8 and revolving the same about the pivot 9 to the position shown in Fig. 3, where the legs 11 100 rest upon the floor and support the outer end of the same. In descending the wall 8 carries with it the door frame 16, which, during the descent is acted on by the counterbalancing cords 20 to raise the same about the hinged braces 18 to occupy an upright position at the outer end of the trough, as shown. Simultaneously, the curtains 34' and 35, by reason of their connection to the door frame 16, are automatically drawn out 110 to inclose the sides of the bath, and through the cord 31 the gooseneck 29 and spray head 30 are moved to elevated position.

It will be understood that the gooseneck 29 may be provided with a valve for regulating the flow of water to the spray head 30, or the head 30 may be arranged to continuously discharge while in the elevated position. In closing the apparatus the door frame 16 is revolved about its hinged connection and the trough 8 raised, assisted by the counterbalance and revolved about the pivot 9 in that manner indicated in Fig. 2.

As more particularly seen in Fig. 7 of the drawings, the casing 1 may be constructed with partitions 45 and 46 at either side thereof, the same forming, with the end walls of the casing, compartments for the counterbalances 24, and for the reception of the curtains 34', the braces 12 and 13, etc.

It will be understood from the foregoing that I have provided a shower bath apparatus of neat and finished appearance, and constructed to be transported as an article 5 of furniture.

I have illustrated and described preferred and satisfactory constructions, but obviously changes could be made in the herein described apparatus which could be used 10 without departing from the spirit of my invention.

I claim:

1. In a shower bath apparatus, the combination of a cabinet, a wall pivoted to said cabinet and adapted to be lowered to form a floor for the bath, counterbalance means for assisting the movement of said wall, a frame for giving access to the bath arranged to normally occupy an upright position 15 at the outer end of said wall and fold down against the latter when the same is raised, and means associated with said counterbalance for moving said frame into an upright position when the wall is lowered, 20 substantially as described.

2. In a shower bath apparatus, the combination of a cabinet, a wall pivoted to said cabinet and adapted to be lowered and form a floor for the bath, braces connected between said cabinet and wall, counterbalance means for said floor, a frame normally occupying an upright position at the outer end of said wall and arranged to be folded down against the latter when the same is 25 raised, means associated with said counterbalance for raising said frame into upright position when said wall is lowered, and curtains connected between said cabinet and frame for inclosing the sides of the bath, 30 substantially as described.

3. In a shower bath apparatus of the character described, the combination of a cabinet, a wall pivoted to said cabinet and arranged to be lowered and form a floor 45 for the bath, a frame for giving access to

the bath normally occupying an upright position at the outer end of said wall, means for hingedly connecting said frame to the wall to permit the same to be folded down against the latter, braces connecting said 50 wall and frame to said cabinet, means for moving said frame into upright position when said wall is lowered, and curtains connected between said cabinet and frame for inclosing the sides of the bath, substantially 55 as described.

4. In a shower bath apparatus, the combination of a cabinet providing a reservoir and waste tank, a wall pivoted to said cabinet and adapted to be lowered and form 60 a floor for the bath, counterbalance means for assisting to move said wall, a door frame normally occupying an upright position at the outer end of said wall and arranged to be folded down against the same, 65 means for moving said frame into upright position when the wall is lowered, a spray device connected to said reservoir and arranged to move within said cabinet when the wall is raised, and means for raising said 70 spray device when said wall is lowered, substantially as described.

5. In a shower bath apparatus, the combination of a cabinet, a wall pivoted to said cabinet and arranged to be lowered and 75 form a floor for the bath, a frame for giving access to the bath and arranged to be folded down against said wall when the latter is raised, and counterbalance means for said wall comprising a stepped support mounted 80 in said cabinet, and a plurality of weights constituting said counterbalance and constructed to rest one on each of the stepped surfaces, substantially as described.

In testimony whereof, I affix my signature, in presence of two witnesses.

CARLOS F. DÁRDANO.
